US00D963886S

(12) **United States Design Patent** (10) **Patent No.:** **US D963,886 S**
(45) **Date of Patent:** **** Sep. 13, 2022**

(54) **PIPETTE BODY**

(71) Applicant: **Mettler-Toledo Rainin, LLC**, Oakland, CA (US)

(72) Inventors: **Thilo Hogrebe**, Hamburg (DE); **Roland Hopp**, Hamburg (DE); **Fred Held**, Hamburg (DE)

(73) Assignee: **Mettler-Toledo Rainin, LLC**, Oakland, CA (US)

(**) Term: **15 Years**

(21) Appl. No.: **29/773,994**

(22) Filed: **Mar. 12, 2021**

(51) LOC (13) Cl. **24-02**

(52) U.S. Cl.

USPC **D24/224**

(57) **CLAIM**

The ornamental design for a pipette body, as shown and described.

DESCRIPTION

FIG. 1 is a top-front perspective view of a pipette body; FIG. 2 is a front view thereof; FIG. 3 is a rear view thereof; FIG. 4 is a right side view thereof; FIG. 5 is a left side view thereof; FIG. 6 is a top view thereof; FIG. 7 is a bottom view thereof; and, FIG. 8 is a bottom-rear perspective view thereof. In the drawing figures, features shown in broken lines indicate environmental subject matter only, and form no part of the claimed design.

1 Claim, 5 Drawing Sheets
